UNITED STATES PATENT OFFICE.

JAMES P. RATIGAN, OF LOS ANGELES, CALIFORNIA.

BEAM BEARING FOR DEEP-WELL PUMPS.

Application filed May 3, 1926. Serial No. 106,461.

This invention relates to an antifriction, greaseless fulcrum means for tilting or walking beam levers.

In many types of machines and apparatus, and particularly in deep-well beam-pump equipment very heavy walking beams are employed. These are usually mounted to oscillate in vertical paths so that their load is taken by trunnion shafts and boxes having horizontal axes, and usually the sweep of the beam is equally divided above and below the horizontal. Because of oscillation about the fixed axis of the bearing, it is clear that the ends of the beam move in true arcs. One end of the pump beam is connected to a polish rod and because of the angular movement of the beam end there is, of course, a decided bending strain on the polish rod as it works in its stuffing box at the head of the pump.

By my present invention I aim to wholly eliminate the use of a lubricant for the beam bearing and still secure a perfectly practicable mounting capable of carrying the full load without heating and freezing of the bearing.

Additionally my purpose, here, is to provide means for materially reducing the undesirable side strain on the polish rod which is, of necessity, incident to the use of a beam oscillating on a constant or invariable axis, such as is the result of use of a simple rotating trunnion, axle or shaft device.

Further, an end I desire to accomplish is ready bodily shifting of the working beam in a direction lengthwise, either way, so as to most effectually determine its setting in relation to other parts of the associated equipment: for instance, to bring its pump end into one or another position over the line of the polish rod.

By the present invention such a longitudinal adjustment of the beam is had without loosening even a nut, or adjustment, or change of any part, excepting the beam itself.

My present invention eliminates trunnions, shafts and axles and provides a device which in one given size, can be used for either light or heavy loads, and, further, is, in the one size, adaptable for use on different size Samson posts.

With the above, an object is to provide a lever having a mounting means affording a progressively changing fulcrum-line contact with a fixed mount whereby to obtain an

effective increase of length of power arm and a shortened end of load arm (in the lever) when the beam is on load lifting stroke. My invention is to secure a maximum leverage of beam on the power arm against a minimum arm on the load side at the moment of initiating load movement.

Another object is to provide against overthrowing or accidental dismounting of the beam from the post.

Further objects and advantages will be made manifest in the ensuing specification of the herewith illustrated apparatus embodying the present improvements; it being understood that modifications, variations and adaptations may be resorted to within the spirit and scope of the invention.

Figure 1 is a side elevation of an un-hitched pump beam, showing the improved mount in side elevation.

Figure 2 is a side elevation of the equipment; parts being broken away.

Figure 3 is a cross-section of the beam and its attached rocker; the post and its beam support or saddle being in elevation.

Figure 4 is a bottom plan of the rocker.

Figure 5 is a side elevation of the rocker.

Figure 6 is a graph indicating by comparison the difference in a rotating, constant axis bearing and the improved floating fulcrum bearing.

The invention is shown as adapted to a walking, pump beam B mounted, by the improved means, upon a support, for instance a Samson post P.

The mounting means consists of a rocker part on the beam and a support or saddle part on the post. It is understood that these "parts" may be combined, in any suitable manner, respectively, with the beam and the post. The parts are here shown as heavy castings attached to the beam and to the post.

The rocker member 2 has a top face to be bolted against the bottom of the beam B, or otherwise suitably fastened. The bottom of the rocker has a wide sole 3 whose face is curved on in a true arc (in edge view) though the curvature need not be limited to true arc form. The sole is thus a portion of a cylinder of rotation having a long radius as compared to the radius of a heel part 4 of the rocker. The beam is preferably balanced when a vertical line passes through the center of the heel 4 and the lowest point of the heel surface (position Fig. 2) when the beam is horizontal. Within the surface

of the heel and sole is a series of transverse teeth 5.

The saddle consists of a heavy top plate 10, to set solidly on the post P, having upwardly projecting side cheeks 11 flanking the side faces of the rocker but not snugly bearing thereon, so that no friction is set up when the rocker rocks, when in place on the upper face of the mounting plate 10. The plate 10 has upwardly extending teeth 12 to mesh with teeth 5 of the rocker. These sets of teeth are much shorter than the width of the sole and heel of the rocker which latter carries and transfers the whole load to the top plate 10. The function of the teeth 5-12 is to form a means to prevent relative end shift of the beam as to the plate. It is desired to eliminate all sliding friction between the rocker and the mount 10. The teeth 5 are formed by spaced valleys in the sole 3 and side play of the beam is prevented by the ends of the teeth 12 or by the side cheeks 11 or by both as may be desired and determined by construction.

The side cheeks receive the ends of a stout pin 14 passing through the rocker body and the rocker or the cheeks have ample opening to allow of rolling action of the beam without restriction of the pin, which forms a means for preventing the beam from jumping off the post or from being overthrown by accident. In the disclosed form the cheeks have large pin apertures 15.

The saddle shown has strong side flanges 16 to embrace the post P and differently spaced pair of bolt holes 17-18 permit of application of bolts 19 close up to the sides of different widths of posts.

The pin 14 is not a pivot for action of the beam, but simply a form of means to keep the beam on top of the saddle.

In operation, the beam rests on a transverse line of contact with the saddle and when the beam is, by any means, tilted this line of contact shifts along the plate 10. Since the beam does not shift the effect is to shorten one end of the lever and lengthen the other. If the sole 3 points toward the pump-rod end A of the lever B, the power end is increased as the pump end goes down. Hence when power is applied to pull up the pump rod the power is applied through greater leverage to start the load.

A further advantage of my trunnionless beam is that instead of the beam end sweeping in an arc concentric to a constant axis (of trunnion) the rocker sole 3 takes a rolling action on the plate and the beam end A moves in a much flattened curtate cycloid path C (Fig. 6) about the floating fulcrum sole 3. This straightening of the beam sweep is especially helpful during the lower half of both the down stroke and the up stroke, in which the polish rod of the pump is least extended from its stuffing box and

has not the give or flexibility it has in its upper half of strokes (up and down).

Therefore while I have gained by elimination of friction rotation (of trunnion) I also gain in the several respects above set 70 out.

It will be seen that the beam has a fair degree of free floating movement on its saddle which allows it to accommodate itself to strains and stresses without a twisting result as occurs in rock-shaft bearings. This freedom avoids friction in bearings.

Suitable guy wire bails 20 may be hung on the bolts 19 to brace the post P.

The advantage of the short radius heel 4 80 is that as the power arm swings down its length is not materially shortened as it would be if the heel were of the same flat arc of the sole 3.

The slots 15 are so proportioned that the beam B, with its attached rocker 2, may be bodily shifted endwise to bring the pump end of the beam into the best working position over the line of pump polished rods. This is done without any adjustment of the 90 rocker 2 as to the beam itself and is provided for by relative adjustment of the rocker teeth 5 along the fixed rack 12 of the saddle.

What is claimed is:

1. A Samson post for deep well pumps having on its top end a plane uninterrupted top load surface, and a walking beam having a rocker portion presenting a longitudinally curved, smooth rolling tread face meeting the said surface in broad, transverse rolling-line contact; whereby to eliminate point contact of the face and the surface under load and to obtain long wear life of the meeting faces and side cheeks limiting 105 side play of the rocker.

2. A Samson post for beam pumps provided with a plane top bearing plate, and a walking beam having a broad, curved faced rocker part bearing and rolling on the said plate along long lines of contact; said rocker part having transverse, medially spaced, rack teeth, and said plate having upstanding, intermediately disposed teeth to loosely mesh in the rack teeth and prevent 115 undue end shift of the beam while working.

3. A Samson post for pumps provided with a top bearing plate, and a walking beam having a broad, curved faced rocker part rolling along the bearing plate; said beam rocker part and said plate having loosely meshing teeth means to prevent creep of the beam, and said teeth means including mutual racks shiftable relatively one on the other to provide an effective change of orbits 125 for the ends of the beam.

4. A Samson post having on its top a bearing plate presenting a smooth load area, and a walking beam having a rocker portion presenting smooth, merging heel and sole 130

tread face rolling on transverse lines along the said plate area, the heel being sharply curved back from the sole to effect a differential action as the beam rolls from the flatter sole.

5. The combination, in a deep well pump, of a Samson post having a plane-faced top plate with upstanding side cheeks and downwardly extending flanges, means passing through the flanges to secure the plate in place on the post, a walking beam disposed above the post and having a rocker, loosely fitting between the cheeks, having a curved rolling face resting upon the top plate and a retaining pin passing from cheek to cheek and through the rocker.

6. The combination, in a deep well pump, of a Samson post having a plane-faced top plate, side cheeks extending up from the plate, means for securing the plate in position on the post, a walking beam having a

rocker with a curved face rolling on the top plate, said beam being bodily adjustable to operate at different positions on the plate to regulate the line of lift on an attached 25 polish rod, and relatively shiftable rack means to loosely retain the beam in any of its working positions.

7. A cradle for a pump walking beam, consisting of a bed part having a seat to rest upon the head of a Samson post and having upstanding side cheeks, a rocker part attachable to the bottom of a walking beam and loosely fitting between the side cheeks and having a smooth rolling face bearing 35 on the said bed part; the mutual parts presenting longitudinally uninterrupted load zones of rolling contact, and a key pin passing through the rocker part and into the bed cheeks to prevent overthrow of the 40 mounted beam.

JAMES P. RATIGAN.
